UNITED STATES PATENT OFFICE.

GEORGE F. STURGEES, OF LEICESTER, ENGLAND.

KNITTING-MACHINE.

SPECIFICATION forming part of Letters Patent No. 632,327, dated September 5, 1899.

Application filed November 14, 1898. Serial No. 696,445. (No model.)

To all whom it may concern:

Be it known that I, GEORGE FREDERICK STURGEES, hosier's engineer, a subject of the Queen of England, residing at the Inglenook, 5 Leicester, in the county of Leicester, England, have invented certain new and useful Improvements in and Connected with Knitting-Machines, of which the following is a specification.

This invention refers to knitting-machines, particularly to those which have two needle-beds coacting.

This invention has for its object to dispense with the pivots, moving cam-plates, carriers, 15 springs, elastic bands, and such like devices now employed to retain or hold webbers in the slideways of the comb of the needle-bed; also, to dispense with the dial-posts, lugs, retarders, and such like devices now employed 20 to normally maintain the fixed relation of the fixed needle-beds; also, to dispense with the weights, rollers, and such like devices now employed to normally hold rib fabric in knitting position and to impart a piercing action 25 to carry free staple to the back of the fabric, obtaining a self-retaining slidable webber device operable from the bed-face and a more elastic and smoother-faced fabric than heretofore.

Figure 1 is a sectional elevation view of co-acting needle-beds of the cylindrical and radial type, cut through on lines A and B of Fig. 2. Fig. 2 is a top view of the needle-beds shown in Fig. 1 with a portion of the radial bed cut away. Fig. 3 is a top view of the detachable part of the first needle-bed separated, showing how it is pieced up; and Fig. 4 is a sectional view of the same through one of the attaching-screws. Fig. 5 is a front 40 elevation view showing a part of the coacting needle-beds and the stitch-hook or web-holder, looking at the right sides of Figs. 1 and 2, the detachable part of the cylindrical bed being omitted in order to show the webber-comb ways and recesses, the first bed being 45 broken away at its upper edge in one part to clearly show the front edge of the second bed. Fig. 6 is a sectional elevation view of a part of the beds with the webbers and the detachable part of the cylindrical bed omitted, clearly 50 showing the combway and recess. Fig. 7 is an under side view of a part of the radial nee-

dle-bed shown in Fig. 1, showing the comb. Fig. 8 is a side view, and Fig. 9 a top view, of a detached webber. Fig. 10 is a side view 55 of a stronger form of webber for use in coarse-gaged machines. Fig. 11 is a view showing another modification of webber and of the top part of a needle-bed in which the detachable part of the needle-bed is omitted. Fig. 60 12 is a side view of the webber shown in Fig. 11, disclosing the manner in which it is connected to its fixing-blade. Fig. 13 is a section view of the fixing-blade detached, cut through on lines C D of Fig. 12. Fig. 14 is a sectional 65 elevation view showing a modified form of webber applied to a well-known combination of coacting cylindrical and conical needle-beds. Fig. 15 is a top view of a portion of the cylindrical needle-bed shown in Fig. 14, 70 showing the webber-cam. Fig. 16 is a front view of a portion of the cylindrical needle-bed shown in Fig. 14, showing the webber-cam. Fig. 17 is a sectional elevation of two coacting needle-beds, showing another form of the 75 webber applied to a well-known combination of flat needle-beds; and Fig. 18 is a plan view of a portion of the needle-beds. Fig. 19 is a sectional elevation, Fig. 20 is a front view, and Fig. 21 a top view, of a portion of an ordinary needle-bed, showing a further modification of webber constructed in accordance 80 with this invention adapted to existing needle-beds.

Referring to Figs. 1, 2, 3, 4, 5, 6, 7, 8, 9, and 85 10, above the face 1 of the first needle-bed is the usual webber-comb 2; also, recesses 3 in the face of the bed, making a continuation of the combways 5, extending downwardly and inwardly from the front to the back of the needles 27 at point 4. At the bottom of each of the combways 5 is provided a slideway-seating 6 and 7, extending up the face side and down the back side 8 of the base of the bed, making a plurality of webber-bearings. 90 Seated in the grooved surface 39 is a detachable part, which is comprised of two parts 40 and 41, pieced up in the groove 39 by attaching-strips 42 and 43, screwed to the ends of the parts 40 and 41 by screws 44, 45, 46, and 100 47. Grooves 49 for the passage of the needles and webber-comb ways 50 in line with the recesses 3, the bottoms of which form the convexed slideway-seatings 51, are provided in

the detachable part. The complete bed forms in the webber-comb open-ended guideways, each of which has a plurality of slideway seatings or bearings, any two of which form 5 sufficient length of bearing to detachably retain a coarse and durable webber.

The second bed 21 has a webber-comb 20, extending from the front to the rear of its needles 36, making broad openings 23 for the 10 passage of the knitted loops and narrow openings 24 in alinement with the combways of the first bed for the reception of the needle-pointed webber-teeth and projecting teeth 22, which serve to hold the fabric up to the piercing 15 action of the webber-teeth and by engagement with the sides of the webbers to hold the two beds locked in a fixed relative position.

The webber 9 (shown in Fig. 8) is provided 20 with a plurality of needle-pointed teeth, comprised of a needle-pointed tooth 10, making a hook 11 for engagement with the newly-formed loops, and a breast 12, over which the thread-loops are drawn, and a needle-pointed 25 hook 13 below the breast 12 for piercing the mesh or loops of the completely-formed fabric to carry free staple through from the face to the back of the fabric and depress the fabric. In order to knit fabric from rough and long 30 staple yarn with a smooth face, extra needle-pointed teeth are added below the breast 12, as seen in Fig. 8, one of which is bent aside to enter the needle-loops. (See 52, Fig. 9.) The webber is also provided with inwardly-projecting shanks 14 and 15 and openings 17 and 18, making a clear (having no cam-foot 35 projections) slide-seating, continued up one side and down the opposite side, forming a plurality of slide seating or bearing edges, 40 which serve by engagement with the slideway seatings or bearings 6, 7, and 51 to make the webber self-retaining in the combways.

The needle-beds and webbers shown are drawn in a very coarse gage in order to clearly 45 illustrate the device; but in practice in such coarse-gaged and strong beds and webbers as those shown, in which there is also sufficient room for the rear shank 14 to be retained, the detachable part 40 and its seating 51 are 50 omitted, as shown in Fig. 6, in which case the webber is made stronger by being shanked, as seen in Fig. 10, its front opening being omitted. Each webber is provided with a cam-recess 19.

55 In working position the webbers protrude from the combways to the face of the bed and are operated by an arch-cam 30, engaging the sides of the recesses 19, secured to a traveling part of the machine 25, comprised of parts 60 25 and 26, joined by pivot 29 and spring-clasp 28, the part 26 of which may be opened for the handling of the needles 27 or webbers 9. An inner swell 33 and outer swells 34 and 35 of the arch-cam 30 slide or reciprocate the 65 webbers in the comb-guideways, the swell 33 withdrawing the needle-pointed teeth from the fabric and from the comb of the second

needle-bed, while the thread is drawn across the breasts 12, and new loops are formed and passed through between the connecting-beds, 70 and the swell 34 or swell 35, according to the direction of knitting, slides the needle-pointed teeth in the opposite direction into the comb of the second bed in a manner as to pierce all loops with which it may come into 75 contact rather than trap or cut the loops upon the second bed, causing the teeth below the breasts to pierce the succeeding courses of loops, carrying loose or free staple through the completely-formed mesh and increasing 80 the elasticity of the fabric by making the loops more round and slides the upper teeth into the comb of the second needle-bed, bridging over the intervening space and making a complete connection with the two beds, except on that section where the swell 33 of the arch-cam withdraws the webber-points from the second combway to allow of the formation and passage of new loops between the needle-beds. 85

In machines of fine gage so much of the substance of the detachable part 40 is cut away by the frequency of the adjoining needle-grooves and combways as to leave insufficient strength or room for the attaching-screws 44, 45, 46, and 47, and consequently such a fine-gaged detachable convex slideway seating or bearing 51 if it could be made in this combined form would be useless. Therefore in such a fine machine the said slideway-seatings are detached from their ring-support, as it were, and made separately in the form of fixing-blades. Each fixing-blade is comprised of the counterpart of a webber inserted in a combway, and bears or carries the webber, 100 making a compound or two-part webber 54 and 56, as seen in Fig. 11. The fixing part 53 is chopped or pressed from the movable toothed part 54 in the position shown in Fig. 12. The cross-bar 55 connects the strip 58 to 105 the body 56 to allow the fixing part 53 to be swung around the shank of the toothed part 54 into the operative position, Fig. 11. The needle-bed has a groove 57, which admits the set-aside part 55 to hold the blade 53, which is 110 wedged in the combway, in position, while the toothed part 54 is reduced on its sides to allow of its sliding freely in the combway in the manner shown in Fig. 11. This compound webber can be detached when the shank 14 is 115 not cut away even by sliding the toothed part 120 backward until the shank 14 passes over the upper edge of the base 1 of the needle-bed, when the fixing part 53 and toothed part 54 can be forcibly withdrawn from the combway and afterward separated. 125

In applying the device to existing coarse-gage machines in which the webbers may be made thick and strong enough to allow of it it is not necessary to construct a special needle-bed. I adapt the ordinary needle-bed, as seen in Figs. 19, 20, and 21. The coarse needles having been replaced by needles having shanks of finer gage in their upper part, a 130

comb is cut in the upper edge of the needle-bed 77, the combways of which are in line with the needle-grooves 76, each combway being provided with a seating up the front and continued down the back or opposite side of the bed, making a plurality of seatings 78 and 80 on the base of the bed 77. The webber 75 is inserted in the comb-slideway, the back shank 79 sliding on the seating 80 and the front shank 74 sliding on the seating 78 inside a needle-groove 76 alongside a needle. Referring to Fig. 19, the arched webber-cam 71, engaging the recess of the webber, fixed on a traveling part of the machine similar to the arched webber-cam before referred to, slides the webber from the full-line position by first lifting and then pressing the webber horizontally to the dotted position while new loops are formed, then sliding it back again to full-line position by drawing it downward.

Referring to Figs. 14, 15, and 16, the device is shown applied to the well-known inverted conical second bed. The slideway-seatings 59 and 60 in the recesses and combways on the base 1 of the bed, beneath the comb 2, and the seating edges of the webbers 61 are necessarily on straight parallel lines, the extremity of the rear shank being in this case pointed and serving the purpose of a fabric-piercing tooth. The comb 69, which extends downward at the back of the needle-tricks and needles 68 of the second bed, holds the fabric up to its piercing action as it enters the comb. The webbers are operated in a similar manner by an arched cam 64, engaging the recess in the webber and secured at the angle shown by screws 66 and 67 to a traveling part 65 of the machine, which in this case is faced up at 70 to the edge of the outer webber-shank, giving the webber further support.

Referring to Figs. 17 and 18, the invention is shown applied to the well-known parallel-bed type of machine, the webber 73 being mounted and operated on the beds 71 and 72 in a similar manner, as will be instantly understood by comparison without further reference.

I am aware that it is common for webbers (web-hooks, web-holders, stitch-hooks, and loopers) to be held up to a straight or curved seating.

I declare that what I claim is—

1. A knitting-machine provided with two needle-beds coating, each having a comb-way for the reception of the same set of webbers, the combways of the first bed provided at their bottoms in the base of the bed with slideway-seatings continued up one side and down the opposite side, forming a plurality of slideway-seatings, detachably bearing webbers provided with needle-pointed teeth, and shanked inwardly with a corresponding plurality of clear seating edges, and means located on the outside of the beds, to slide the pointed teeth into and out of the combways of the second bed and the fabric, serving to rigidly hold the needle-beds in fixed

relative position, and pierce and depress the fabric made on the two beds, substantially as and for the purposes set forth.

2. A knitting-machine provided with two needle-beds coating, each provided with combways for the reception of the same set of webbers, and slideable webbers having needle-pointed teeth mounted in the combways of the first needle-bed, and means to reciprocate their needle-pointed teeth into and out of the combways of the second needle-bed, whereby the webbers pierce each succeeding course of loops and depress the fabric, carrying free staple through to the back, and holding the two beds in correct alignment to each other, substantially as and for the purposes set forth.

3. A knitting-machine provided with two needle-beds coating, each provided with combways containing the same set of slideable webbers, bridging over from bed to bed above the knitted loops, locking and holding the two beds in correct alignment with each other, and means to recede the webbers out of engagement with the combways of the second bed to allow of the formation and passage of new loops between the two beds, substantially as and for the purposes set forth.

4. A knitting-machine provided with a needle-bed having webber-comb ways and recesses in its face, extending downwardly and inwardly to the rear of its needles, each of which is provided with a slideway-seating, continued up one side and down the opposite side, forming a plurality of slideway-seatings detachably bearing a webber shanked inwardly with a corresponding plurality of clear (having no cam-foot projections) slide-seating edges, and means, located forward of the bed-face, to operate them, substantially as and for the purposes set forth.

5. A knitting-machine having a needle-bed provided with webber-comb ways, extending downwardly and inwardly to the rear of its needles, each of which has a plurality of oppositely-posed slideway-seatings, and containing webbers, each of which has an inwardly-shanked body, provided with seating edges conforming to the slideway-seatings, mounted as to be operable from the bed-face, and means forward of the bed-face to operate them, substantially as and for the purposes set forth.

6. A slideable webber comprised of a blade having a hooked or toothed upper part, shanked inwardly to a plurality of clear (having no cam-foot projections) seating edges, said edges being on lines parallel to each other, adapted to slide in and upon the base of the needle-bed, provided with a corresponding plurality of slideway-seatings, and be operated by a cam located forward of the needle-bed face, substantially as and for the purposes set forth.

7. A slideable webber double-shanked inwardly from the hooked or toothed part, provided with a plurality of clear (having no

cam-foot projections) seating edges on lines parallel to each other, substantially as and for the purposes set forth.

8. A slideable web holding and piercing device, comprised of a blade having a plurality of needle-pointed loop or fabric engaging parts or teeth located beneath each other on its fore part, adapted to slide in the combways of a needle-bed, and means to reciprocate it, whereby the upper tooth engages the newly-made loops, and the lower tooth pierces the loops of the completely-formed fabric, substantially as and for the purposes set forth.

15. A slideable webber provided with a fabric-piercing tooth situated below the breast or thread-drawing part, adapted to slide in the combways of a needle-bed, and be reciprocated as to pierce the loops or mesh of the 20 completely-formed fabric, substantially as and for the purposes set forth.

10. A slideable webber, the hook or tooth of which is brought to a needle or piercing point, adapted to pierce any knitted loop or thread 25 with which it comes in contact rather than trap or cut it, substantially as and for the purposes set forth.

11. A knitting-machine having a needle-bed provided at its top with webber-comb ways

and two-part or compound detachable webbers, each webber comprised of a fixing-blade secured in its combway, making in the combway a webber-guideway, having a plurality of slideway-seatings, and a hooked movable blade slidably fitted in the guideway so made 35 upon the fixing-blade, the whole of the compound webber being detachably retained in its combway, substantially as and for the purposes set forth.

12. A knitting-machine having provisions 40 for piercing and depressing the fabric between coacting beds, and for locking the two needle-beds together, consisting of needle-pointed toothed webbers, detachably sliding in the first bed upon a plurality of bearings in 45 the combways, which extend downwardly and inwardly to a point in the rear of the needles, and engage the teeth of a combway, which extend downwardly and inwardly to the back of the needles of the second bed, in a manner 50 as to be operable from the face side of the needle-beds, substantially as and for the purposes set forth.

Dated this 5th day of November, 1898.
